UNITED STATES PATENT OFFICE

GUSTAV O. WILMS, OF MILWAUKEE, WISCONSIN, ASSIGNEE, BY MESNE ASSIGNMENTS,
TO THE RELIANCE COMPANY, OF MILWAUKEE, WISCONSIN, A CORPORATION OF WIS-
CONSIN

RADIO APPARATUS

Continuation of application Serial No. 549,352, filed April 3, 1922. This application filed July 18, 1922,
Serial No. 574,802. Renewed April 10, 1929.

This application is a continuation of application Serial No. 549,352, filed April 3, 1922, as to matter common to both applications.

5 The invention relates to radio apparatus.

The radio apparatus to which the invention applies in particular has an electronic valve or tube and a rheostat for regulating the same.

10 An electronic valve is very sensitive and an infinitesimal variation of the resistance in any circuit thereof causes a pronounced change in the action of the valve.

If an electronic valve in a radio receiver is controlled by a rheostat which has infinitesimal irregularities in the variations of its resistance, the receiver will produce objectionable noises and be difficult to adjust.

An object of the invention is to obtain a 20 smooth and regular variation in the action of electronic valves employed in radio apparatus.

Another object is to provide radio apparatus in which the resistance in a valve circuit 25 may be gradually and uniformly varied.

According to the invention, a carbon disc resistor is connected in circuit with the electronic valve and has the pressure thereon varied by a low tension spring which is controlled by an actuator and proportioned to 30 vary a low pressure upon the resistor and cause a gradual and uniform variation in the resistance thereof through a wide working range.

35 Applications of the invention are shown in the accompanying drawing in which the views are as follows:

Fig. 1 is a diagram of a radio receiver showing the regulating rheostat connected in 40 circuit with the cathode of an electronic valve which is employed as a detector.

Fig. 2 is a diagram showing the regulating rheostat connected in circuit with the supplemental anode of an electronic valve.

45 Fig. 3 is a diagram showing the regulating rheostat connected in circuit with the cathode and the anode of an electronic valve.

Fig. 4 is a section through the rheostat shown in Figs. 1 and 3.

50 Fig. 5 shows comparative curves illustrat-

ing the characteristics of the regulating rheostat and prior rheostats.

Fig. 1 will first be described. It shows a radio telephone receiving system in which telephone receivers 1 are connected to a grounded aerial 2 by a transformer 3 and a regulated detector 4. The transformer may have a variable primary.

The detector 4 takes the form of an electronic valve comprising an evacuated vessel 5 having therein a cathode 6, an anode or plate 7 and a supplemental electrode or grid 8.

The cathode 6 is normally heated by current supplied from battery 9, or other source, the amount of current being regulated by a rheostat 10.

The telephone receivers 1 are connected in series with a battery 11 between the cathode 6 and the anode 7. Battery 11 maintains the anode 7 at positive potential with respect to the cathode 6.

The supplemental anode 8 is connected to one terminal of the secondary of transformer 3, the other terminal of which is connected to the cathode 6.

A condenser 12 of low capacity shunted by a high resistance 13 may be connected between the transformer 3 and the electronic valve 4. The telephone receivers 1 may have a condenser 14 connected in parallel therewith.

The rheostat 10 is employed to vary the resistance in circuit with battery 9 so as to vary the current supplied to the cathode 6 and thus vary the temperature thereof.

The regulating rheostat may be located in the grid circuit of the electronic valve as shown in Fig. 2 or in the plate circuit as shown in Fig. 3.

The regulating rheostat which is a pressure rheostat comprises in general, resistors 20 and an actuator 21 for compressing and decompressing the same to vary the resistance thereof.

Each resistor is made of a plurality of contacting electrodes 22 of graphite or other suitable material. The electrodes may take the form of flat disks.

Each end disk 23 is thicker than the inter-

mediate disks and may be made of metal silver plated to insure good electrical contact with co-operating parts.

The resistors are located in spaced pockets of an insulating casing 24 made of porcelain or other suitable material ordinarily held in the position shown in Fig. 4.

The inner end disk 23 of each resistor is in contact with the head of a hollow rivet 25 by which terminals 26 are fastened to the casing 24. The rivets 25 also fasten to the casing contact springs 27 which when electrically connected short circuit the resistors.

The actuator 21 comprises a micrometric screw 28 mounted on a rotatable spindle 29. The screw 28 is threaded into a nut 30 fastened to the casing cover 31.

The inner conical end 32 of the spindle 29 fits in the conical recess 33 in the outer end of a guide pin 34, the inner end of which is located in an aperture 35 in the casing.

The angle of the conical end 32 is less than that of the conical recess 33 so as to reduce the contacting surfaces thereof and allow the conical end to seat properly in the recess.

The guide pin 34 carries a bridging contact spring 36 loosely seated against a shoulder formed on the guide pin.

The guide pin 34 and the bridging contact spring 36 are adapted to be moved inwardly against a spring 37.

The outer ends of the bridging contact spring 36 are adapted to engage the outer end disks 23 and thereby connect the resistors in series.

The bridging contact spring 36 may be silver plated to insure good electrical contact with the end disks.

The bridging contact spring 36 due to its resiliency absorbs irregularities in pressure due to any irregular movement of the actuator, and enables the resistance to be varied steadily and smoothly.

The spring 37 tends at all times to force the bridging contact spring 36 out of contact with the end electrodes of the resistors. Thus when the actuator is at the outer limit of its movement the bridging contact spring 36 is forced out of contact with the end electrodes.

The spring 37 also assists the bridging contact spring 36 in absorbing irregularities in pressure due to any irregular movement of the actuator.

A shoulder 38 on the guide pin 34 engages the base of the casing thus limiting the inward movement of the guide pin and the compression of the resistors.

The outer end of the spindle 29 is provided with a knob 39 by which the micro screw is threaded through the nut.

The inward movement of the actuator and guide pin causes the outer ends of the bridging contact spring to engage the end disks of the resistors and compress the resistors to decrease the resistance thereof.

Movement in the opposite direction decompresses the resistors to increase the resistance thereof.

When at the limit of its outward movement the bridging contact spring is out of contact with the end disks. 70

The electrodes of the resistors are thus relieved of pressure, and the circuit between the resistors is opened.

When the guide pin 34 is at the limit of its inward movement it engages contact springs 27 thus short circuiting the resistors and removing the same from circuit. 75

The conical connection between the spindle and guide pin co-operates with the bridging contact spring to equalize the pressure on the two resistors. 80

The cover 31 may be fastened to the casing 24 by rivets 40 or other fastening means.

The cover 31 is provided with mounting lugs 41 by which the rheostat is fastened to a panel 42 or other support so the resistors will occupy the position shown in Fig. 4. 85

The angle of the threads of the micrometric screw actuator is approximately 1.37°. 90

The axial movement of the actuator is less than twenty-five thousandths of an inch for each complete turn thereof.

It is therefore possible to vary the resistance steadily, smoothly and accurately throughout the range required for the regulation of the valve and obtain very accurate and sharp tuning of the circuits of the radio telephone receiving circuits wherein the radio apparatus is employed. 95

Of course, other forms of the pressure regulating rheostat such as are shown in my co-pending application Serial No. 574,803 filed July 13, 1922, may be employed in the same manner as that disclosed herein. 100

Fig. 5 shows resistance curves of the pressure rheostat and wire rheostats. The ordinates represent resistance and the abscissæ movement of the actuator.

Curve A illustrates the smooth and steady variation of the resistance of the pressure rheostat. 110

Curve B illustrates the variation in resistance of a step-by-step wire rheostat.

Curve C illustrates the variation in resistance of a vernier step-by-step wire rheostat. 115

A step-by-step wire rheostat is irregular in action due to many causes among which are variations in pressure between contacts and changes between values of resistances. 120

The irregularities are uncontrollable. Therefore when employed to regulate an electronic valve employed in a radio telephone system, the irregular action of the valve results, causing the telephone receiver to produce objectionable noises and disturbances. 125

While in some instances the irregularities in resistance may not be great in themselves, they are greatly magnified by the electronic valve which it regulates so that objectionable 130

noises and disturbances are produced by the telephone receiver.

All such objectionable noises and disturbances seriously interfere with the tuning of the apparatus of the receiving system.

An inspection of the curves of Fig. 5 readily shows that the radio apparatus wherein are combined an electronic valve and the pressure regulating rheostat overcomes the objectionable noises inherent in prior apparatus.

10 The invention set forth herein is, of course, susceptible of other embodiments and adaptations.

The invention claimed is:

15 1. A radio apparatus comprising an electronic valve, a carbon disk resistor connected in circuit therewith to adjust and control the action thereof, a low tension spring proportioned to vary a low pressure upon said resistor and thereby cause a gradual and steady variation in resistance through a wide working range to obtain a smooth and regular variation in the action of said valve, and an adjustable actuator for operating said 20 spring.

25 2. A radio apparatus comprising an electronic valve, a carbon disk resistor connected in circuit therewith to control the action thereof, a low tension spring proportioned 30 to vary a low pressure upon said resistor and thereby cause a gradual and steady variation in resistance through a wide working range to obtain a smooth and regular variation in the action of said valve, and a screw 35 actuator for operating said spring.

40 3. A radio apparatus comprising an electronic valve, two carbon disk resistors connected in circuit therewith to control the action thereof, a low tension spring proportioned to vary a low pressure upon said resistors and thereby produce a gradual and steady variation in resistance through a wide working range to obtain a smooth and regular variation in the action of said valve, and 45 an adjustable actuator for operating said spring.

45 4. A radio apparatus comprising an electronic valve, two carbon disk resistors connected in circuit therewith to control the action thereof, a low tension spring proportioned to vary a low pressure upon said resistors and thereby produce a gradual and steady variation in resistance through a wide working range to obtain a smooth and regular variation in the action of said valve, and 55 a screw actuator for operating said spring.

In witness whereof, I have hereunto subscribed my name.

GUSTAV O. WILMS.
